UNITED STATES PATENT OFFICE

CHARLES WIGHT MACMILLAN, OF CAMBRIDGE, MASSACHUSETTS

AUTOMATIC CARBURETOR CHOKE MECHANISM

Application filed September 8, 1930. Serial No. 480,205.

This invention is a carburetor choke mechanism which in conjunction with the throttle, the choke valve, and a thermostat functions automatically to regulate the carburetor choke valve on a gasoline engine under all conditions of operation.

The object of this invention is to provide an automatic means of opening, closing, and regulating the position of the carburetor choke valve under all conditions of engine temperature, and under all conditions of power requirements when the engine temperature is below its thermal normalcy. The advantages of this invention lie in the fact that it renders it unnecessary to manually operate the carburetor choke control, and thereby eliminates the necessity of regulating this control by hand when starting a cold engine. Furthermore, this invention eliminates the tendency to over-choke and under-choke the carburetor during the running period required by the engine to gain its normal temperature.

I declare the following to be an exact description of the invention.

Referring to the drawing, Figure 1 is a skeleton, kinematic sketch of the mechanism showing six different phase positions of the said mechanism. Figure 2 is a side elevation of an automobile engine showing the carburetor and the mechanism applied to the choke valve. Figure 3 is a front elevation of the engine showing the mechanism applied to the carburetor, and the thermostat control which allows the choke valve to open as the engine temperature rises.

A detailed description of the invention is as follows. Referring to the drawing, numbers 1, 2, 3, 4, 5, and 6 denote different positions of the mechanism. 23 denotes the throttle control rod which, in an automobile, connects the foot pedal with the carburetor throttle valve. 22 denotes an arm having a fixed pivot, 16, and being connected to the throttle rod, 23, by means of the pin joint, 14. Number 17 denotes an arm which is connected to arm 22 by means of a pin joint denoted by 19, and to a slider denoted by 12 also by means of a pin joint. 13 denotes an arm having a fixed pivot denoted by 21. Number 11 denotes

a slider to which the arm 13 is connected by means of a pin joint. 20 denotes a pin extension of the carburetor choke valve. 10 denotes an arm which is connected firmly to the pin 20, and which operates the choke valve 55 thereby. 27 denotes a fixed stop post against which the arm 10 may strike thus restricting the backward movement of this arm. 30 denotes an arm which is operated from a thermostat, and which rotates thru a negative or 60 positive angle as the temperature of the engine increases or decreases respectively as viewed in Figure 1. Number 15 denotes the position assumed by the pin joint 14 when the throttle is open, while 18 denotes the position assumed by the pin joint 19 under the same conditions. 7 denotes an arc described by a point on the arm 10 as this arm rotates; the said point coinciding with the position of the center of the slider 11 in phase position 65 number 1. Number 8 denotes an arc described by the center of the slider 11 as arms 10 and 13 rotate. 28 denotes the intake manifold. 26 denotes a spring which is mounted at the pivot of the arm 10 and which holds this arm 70 against the thermostat-controlled arm 30. Number 29 denotes a thermostat which in Figure 3 is shown to be in contact with the cylinder block where the actual engine temperature governs its operation. 24 denotes 80 the carburetor. 25 denotes the throttle valve. Number 31 denotes the conventional butterfly valve of the throttle. Number 32 denotes the choke valve.

A complete explanation of the operation of 85 this invention and the kinematic movements of this mechanism is as follows.

The correct operation of a carburetor choke valve under all conditions must necessarily be a function of two variable factors, 90 namely, engine temperature, and power required. In this invention the temperature variation is converted into mechanical motion thru the medium of a thermostat of which there may be many different, individual designs. The variable factor of power requirement is controlled by means of the mechanism in this invention. The power required is obviously a variable factor since an engine will run smoothly under a small 95

load when below its normal temperature even though the fuel mixture be the same as that required when the engine is running at its normal temperature. However, while the engine is running in this condition if the load is suddenly increased, the richness or density of the fuel mixture must simultaneously be increased to prevent the stopping of the engine. The present conventional means of enriching the fuel mixture when required by a cold engine is by the manual operation of the carburetor choke control. This is invariably necessary with all automobile engines during the warming period required to bring the engine temperature up within its normal operating range. This invention brings together the change in engine temperature and the required choking of the carburetor by means of a thermostat and the disclosed mechanism, both operating in conjunction with each other to correctly and automatically control the carburetor choke during all of the foregoing conditions under which the engine must run. Referring to Figure 1 of the drawing it will be noted that the controlling pin of the carburetor choke valve is denoted by 20. The arm 10 is connected to this control thereby opening and closing the said valve as the said arm moves clockwise or counterclockwise respectively. The thermostat-controlled arm denoted by 30 moves clockwise and counterclockwise as the engine temperature increases and decreases respectively. The arm 10 rests against the thermostat arm 30 and is held in this position by means of the spring 26. When the engine is started the choke valve must be closed to a certain extent depending on the temperature of the engine at the time of starting. This is automatically performed by the thermostat-controlled arm 30 which is so adjusted in connection with the arm 10 that it will hold this arm in the correct position for starting the engine under all general temperature conditions. As the engine becomes warm the thermostat arm 30 rotates clockwise thus allowing the arm 10 to move likewise and thereby opening the choke valve. At any time during the warming period required by the engine it may be necessary to operate the choke valve. Such a moment will occur when the power output is insufficient due to a fuel mixture which is too thin to provide the combustion necessary for the power required at the temperature under consideration. In order that the choke valve may operate correctly at any moment during the warming period it is necessary to provide a means of steadily diminishing the allowable amount of choking action as the engine temperature rises. The mechanism of this invention meets this requirement by means of the arm 13 which rotates on the pivot 21 and the arm 10 which rotates about the pivot 20, the two arms being connected by means of

the slider 11. While rotating in a clockwise direction the slider 11 moves outwardly on the arm 10 describing the arc denoted by 8, while a corresponding point on arm 10 in position 1 describes the arc denoted by 7. At any time when additional power might be required the throttle would be suddenly opened causing arm 22 to swing about its pivot 16 thus pulling the arm 13 and hence the arm 10 in a counterclockwise direction thereby choking the carburetor. From Figure 1 it may be seen that the slider 11, during its clockwise rotation, in being pulled counterclockwise by a succession of movements of the throttle arm 23, will move back each successive time to a point less distant from the final outward position denoted by 6. In consequence the arm 10 is moved counterclockwise to a succession of positions each being less distant from the final position thereby providing a diminishing amplitude of operation of the choke valve. The foregoing is evident from the fact that the slider 11 must travel back over a greater segment on arc 8 than the corresponding segment on arc 7. Thus when the mechanism is in position 3 the indicated movement of the throttle rod 23 moves the arm 10 counterclockwise to position 2. Similarly from position 5 the arm 10 is moved back to position 4. When the thermostat arm 30 reaches a position corresponding to the normal operating temperature the arms 17 and 13 lie in the same straight line. Hence in this latter position a movement of the throttle arm has no further effect on the mechanism.

In operation the movements of this mechanism are precisely as heretofore described. The choke valve is closed or partly closed by an opening movement of the throttle, and is opened by means of a spring as the thermostat arm which checks this opening movement retreats due to a rising temperature. The mechanism is to be adjusted by setting the adjustable pivots in the desired positions. When the engine becomes warmed to its operating temperature no further choking is necessary and, after this point is reached, any movement of the throttle has no further effect on the choke valve, but when the engine becomes cooled subsequent to stopping it is evident that the thermostat arm moves so as to partly close the choke valve. The thermostat thus effects both an opening and closing movement of the choke while the throttle effects only a closing movement of the said choke. Furthermore, smooth operation of the engine is inherently provided for by the actual operation of the sliders on their respective arms. For example, as the throttle is suddenly opened at any moment when the mechanism is in an intermediate position the friction caused by the sudden pressure of the sliders on their respective arms causes the mechanism to move counterclockwise to the

correct choking position. The mechanism almost immediately begins to return to its former position due to the sliding action of the sliders and the force exerted by the spring 26 on the choke valve arm 10.

5 From the foregoing description it may be seen that this invention is completely automatic in its operation, and will operate to definitely control and regulate a carburetor choke valve to which it is applied. Means 10 of adjusting this mechanism for each individual engine may be provided by means of changing the position of the fixed pivots 16 and 21, and the stop post 27, with relation to each other. This mechanism may be compactly inclosed in a box-like housing for the purpose of improving its appearance and protecting it against dust and possible damage.

20 What I claim is:

1. An automatic carburetor choke mechanism operating in conjunction with a throttle valve control to which it is attached and a movable thermostat-controlled piece with 25 which it comes in contact, thereby correctly regulating the choke valve of a carburetor.

2. An automatic carburetor choke mechanism operating in conjunction with a throttle valve control to which it is attached and 30 a movable thermostat-controlled piece with which it comes in contact, thereby correctly regulating the air-intake valve of a carburetor.

3. An automatic carburetor choke mechanism operating in conjunction with a throttle valve control with which it comes in contact and a movable temperature-controlled piece with which it comes in contact, thereby correctly regulating the air-intake valve of 40 a carburetor.

4. An automatic carburetor choke mechanism consisting of an arm being attached to an extension of a carburetor choke valve, said extension being rotatable about its longitudinal axis in operating said valve, and said arm being perpendicular to said axis; a slider mounted on and being movable longitudinally along said arm; an arm being attached to said slider by means of a pin joint and also being attached to a fixed pivot and movable about said pivot; a second slider mounted on and being movable along the last said arm; an arm being attached to the last said slider by means of a pin joint; a fourth arm being movable about a fixed pivot and being connected to the last said arm by means of a pin joint, said fourth arm being connected to a throttle control rod by means of a pin joint.

5. An automatic carburetor choke mechanism consisting of an arm being attached to a carburetor choke valve control; a second arm having and being movable about a fixed pivot and being connected to first said arm 65 and movable longitudinally along first said

arm at the point of connection; a third arm being connected to said second arm and linking said second arm with a throttle valve control.

6. An automatic carburetor choke mechanism 70 in which an arm extends from the choke valve control and operates said valve by means of a slider on said arm, said slider being attached by means of a pin joint to a second arm, said second arm being rotatable about a fixed pivot, said pivot being eccentrically located with respect to the pivot of the first said arm, an adjustable, fixed stop post against which the first said arm may strike thereby restricting the backward 75 movement of said arm and in consequence restricting the choking movement of the choke valve.

7. An automatic carburetor choke mechanism 80 consisting of two arms each of which rotates about its own fixed pivot, said pivots being eccentrically located, said arms being connected and having relative motion at the point of connection, one of the said arms being the direct means of operating the carburetor choke valve and being held by means of a spring against a movable thermostat-controlled arm, said thermostat-controlled arm being the means of restricting the movement 85 in one direction of said choke valve operating arm.

8. A mechanism for automatically operating and regulating a carburetor choke valve by means of an arm being pivoted at one extremity on an extension of said valve; a 100 slider being confined to and movable longitudinally along said arm; a second arm being pivoted at one extremity and attached to said slider by means of a pin joint at its other extremity; a second slider being confined to 105 and movable longitudinally along said second arm; a third arm being attached by means of a pin joint to said second slider and being linked with a throttle control lever, a throttle opening movement of said lever 110 providing the force by means of which the mechanism is actuated to correctly and automatically operate the choke valve of a carburetor when an increased density of fuel mixture is required.

9. An automatic carburetor choke mechanism 115 operating in conjunction with a throttle control arm and a thermostat-controlled arm to correctly regulate the choke valve of a carburetor by means of two arms each being 120 movable about its own fixed pivot, one of said arms operating said choke valve and having its movement in one direction restricted by said thermostat-controlled arm while its movement in the opposite direction 125 is restricted by a fixed stop, the other said arm being connected to a slider by means of a pin joint and said slider being attached to and movable along the first said arm, a second slider being attached to and movable 130

along the second said arm, said second slider having a pin joint to which a third arm is attached, said third arm being linked with said throttle control arm; the complete mechanism operating as and for the purpose substantially set forth.

In testimony whereof I affix my signature.

C. W. MacMILLAN.
